UNITED STATES PATENT OFFICE.

HOLTON D. ROBINSON, OF NEW YORK, N. Y.

CABLE SQUEEZER.

Application filed June 14, 1926. Serial No. 115,788.

This invention relates to mechanism for forming parallel bundles of wires into a cylindrically shaped mass, and is especially applicable to the squeezing of the numerous 5 bundles of wires in the incompletely shaped cables of suspension bridges, into cylindrical form previously to the wrapping of the cables or to the attachment of the suspenders.

I have found that cable squeezers of the 10 design illustrated in my prior Patent No. 926,609, dated June 29, 1909, are unsuitable for the formation of cables of large diameter by reason of the fact that the operating force on the mechanism is applied in a direction 15 tangent to the cable surface wherefore much of the force acts indirectly on a part of the cable and does not produce the full effect desired, the tendency being toward the formation of a cable elliptical instead of circular 20 in cross section.

In my improved mechanism, the force is applied radially of the cable at as many points as may be found desirable preferably by means of a series of more than two independently movable compressors acting directly against the surface of the cable, whereby all of the pressure exerted by the mechanism is utilized to do the desired work 25 of forming the cable into shape.

30 In the laying of suspension bridge cables, individual wires subsequently formed into circular bundles of wires, suitably bound together, are drawn across between the bridge towers and additional similar bundles are arranged 35 concentrically about the first bundle until the required number of wires needed to complete the cable are stretched between the towers. The cross section of the series of the bundles so arranged is therefore substantially 40 hexagonal, instead of circular. It then becomes necessary to put pressure upon the bundles preferably at the points forming the corners of the hexagon, so that the individual bundles may be broken up, and the 45 spaces between bundles may consequently be filled up by the wires separated therefrom to form a compact mass of wires, each of which is in intimate contact with all of the adjacent wires.

50 My invention contemplates the provision of means for applying the requisite pressure in the most direct and effective manner and includes a frame on which are mounted a series of radially movable compressors 55 adapted to act on the wires in the aforesaid bundles in such a manner as to force them

into the desired positions. The various objects of my invention will be clear from the description which follows and from the drawings, in which,

60 Fig. 1 is a front view of that form of my device designed for use in connection with large cables.

Fig. 2 is a plan view and partial horizontal section of the same.

65 Fig. 3 is a front view of the form suitable for smaller cables, and

Fig. 4 is a bottom plan view of the same.

In the practical embodiment of my invention, I provide a frame designated generally 70 by the numeral 10, which is formed of sections or segments removably attached to each other to permit the frame to be opened and passed about the cable to be squeezed into shape at any desired place along the length 75 of the cable. As shown in Figs. 1 and 2, each of the frame segments 11 takes form of one of the sides of a polygon which is preferably a hexagon, for the reasons hereinbefore pointed out. The segment 11 consists 80 of a pair of oppositely disposed channels 12 arranged back to back, the channels being made somewhat shorter than the length of the side of the polygon to allow for the insertion and attachment therebetween of the 85 bearing 13. The cylinder 14, forming the main part of the bearing, is arranged between the ends of adjacent segments 11 and carries the plates 15 spaced apart a sufficient distance to fit between the backs of the channels 12. For reinforcing the plates, a bracing web or rib as 16 may be extended therebetween. Bolts as 17 are passed through suitable holes in the channels 12 and the plates 15 for removably securing the frame 90 parts together.

95 Into the preferably cylindrical opening 18 of each of the bearing cylinders 14, is driven the bushing 19, which is suitably flanged at its innermost end as at 20. The 100 ram 21 may be moved axially in the bushing 19 by means of hydraulic pressure in the usual manner, the liquid entering the opening 22 at the outermost end of the bushing. For forming a leak-proof joint between the 105 ram and wall of the bushing, the packing 23, held in place on the ram by a suitable nut as 24, is provided. It will be seen that the ram 21 is moved radially of the frame 110 by the pressure thereon and is guided in its bodily radial movement by the walls of the bushing 19.

The ram is secured to compressor member 25, of which a series is provided, by the insertion thereof into the hole 26 of said member, a suitable pin or bolt 27 preventing the separation of the parts. It will be understood that for cables of large diameter, it is advisable to cause the compressor members to exert pressure on the cable radially preferably at the corners of the hexagon into which the bundles of wires naturally form, at which corners the most force is required. The larger the cable diameter, therefore the more numerous will be the sides of the polygonal frame within reasonable limits, and consequently, the more compressor members 25 will be used, and conversely, the smaller the cable diameter, the less compressor members will be needed, provided that not less than three are employed. In the squeezer used for smaller cables, it will be seen that the construction of the frame segments may also be simplified, as will be pointed out more fully hereinafter. It is preferable however, to use the hexagonal frame and six compressor members for large cables, and the triangular frame and three compressor members for the smaller cables.

The compressor member for all sizes of cables however, is substantially the same, the only difference being in the angle subtended thereby. For instance, where six compressor members are used as in Figs. 1 and 2, the angle subtended by each will be somewhat greater than 60° and where only three are used as in Figs. 3 and 4, the angle subtended by each will be slightly greater than 120°. Each of said members however, preferably has its greatest thickness at 28, about its center line where the thrust is greatest, its least thickness at the ends, 29 and 30 and has an inner cylindrical surface 31 of the same curvature as that of the finished squeezed cable. The end 29 of the compressor member is made in the form of a tongue, while the end 30 has a groove in the middle thereof adapted to receive the tongue end 29 of the adjacent member, so that said members are arranged in the frame in overlapping or interlocking relation, while each may be moved independently of the others, if desired, through the ram to which it is attached. In the operation of my improved cable squeezer, however, I prefer to supply liquid uniformly and simultaneously to all of the rams 21 so that the pressure exerted by each of the compressor members on the cable is substantially the same and the entire outer surface of the cable is brought to its final position at about the same time. Referring now to the frame used for smaller cables as shown in Figs. 3 and 4, the channels 12 may be dispensed with, as may the separate bearing 13, and in place thereof, the segment 32 may be used, consisting of a single piece of which the bearing 33 may

be an integral part. One end 34 of each of the segments 33 preferably terminates in a tongue, while the other end 35 may terminate in a suitable groove 36 adapted to receive the tongue 34 of the adjacent frame 70 segment. The ends of the segments have holes therein through which a suitable pin or bolt 37 is passed for removably holding the segments in place.

It will be understood that either type of frame shown or any other suitable type may be used in connection with my improved device, provided that the frame is stationary and rigid while in operation to allow the compressor members to operate properly. It will further be understood that the embodiments of my invention shown and described are intended to be merely illustrative and that various changes may be made therein and equivalents substituted, falling within the scope and range of the appended claims.

I claim:

1. In a squeezer for suspension bridge cables, adapted to be arranged in position at various points in a cable for exerting pressure thereon, a series of stationary frame segments, each subtending a central angle not greater than 120°, means for detachably securing said segments together, a series of independently movable cooperating compressor members arranged for movement radially only of and relatively to said segments, a ram at the outer end of each of said members, and a cylinder having an opening in the end thereof, for said ram whereby said ram may be operated by the hydraulic pressure of a liquid forced through into said cylinder through the openings thereof.

2. In mechanism of the character described, a movable compressor member, a stationary polygonal closed frame adapted to be arranged about a cable for supporting said compressor member, a hydraulic cylinder at each of the corners of said frame, and a ram on said compressor member movable in said cylinder, whereby said member may be moved bodily toward the center of said frame and relatively to said frame.

3. In a squeezer for suspension bridge cables, a series of frame segments, means at the ends of said segments for detachably securing said segments together to form a stationary, rigid, polygonal frame, adapted to be arranged about a cable, a series of independent, interlocking compressor members, a cylindrical inner surface of predetermined curvature on each of said members arranged to form a complete cylindrical surface of predetermined curvature at the innermost positions of said members and means for allowing axial movement of each of said members bodily relatively to and toward the center of said frame comprising a hydraulic

cylinder at each of the corners of said frame, and a ram on the outer end of each of said members movable axially in the cylinder.

4. In a squeezer for suspension bridge cables, a polygonal frame adapted to be arranged about a cable and having a series of radial cylindrical openings at the corners thereof, a series of compressor members, and a cylindrical ram detachably connected to each of said members and arranged for bodily radial movement by hydraulic pressure thereupon in one of said openings.

5. In a squeezer for suspension bridge cables, a regular, closed polygonal frame of little altitude adapted to be opened and arranged about a cable and having a series of radial openings at the corners thereof, a series of independent interlocking compressor members, a cylindrical inner surface of predetermined curvature on each of said members, and a ram connected to each of said members and arranged for bodily radial movement in one of said openings relatively to said frame.

25 6. In a squeezer for suspension bridge cables, a series of frame segments, bolts for detachably securing said segments together to form a stationary, rigid, polygonal frame, adapted to be arranged about a cable and moved from place to place thereon, bushings each having a cylindrical opening therein arranged radially of and at the corners of said frame, a series of independent interlocking compressor members, a cylindrical inner surface of predetermined curvature on each of said members arranged to form a complete cylindrical surface of predetermined curvature at the innermost positions of said members, and a cylindrical ram secured to each of said members and movable bodily axially and radially of the frame by hydraulic pressure in one of said bushings, whereby the cable may be changed from a hexagonal to a circular cross-section.

45 7. In a movable squeezer for suspension bridge cables, a compressor member, substantially symmetrical about its axis and having a cylindrical inner surface of predetermined

curvature terminating in a tongue at one end and a groove at the other end adapted to receive the tongue of a similar member, and means for guiding said member for allowing only axial movement thereof comprising a segmental polygonal frame of comparatively little altitude adapted to be opened for passage about a cable and rigidly closed thereafter, and a bushing at a corner of said frame adapted to engage the outer part of said member.

8. In a movable squeezer for suspension bridge cables, a series of similar compressor members separate and independent of each other and each subtending an angle not greater than 120° and means for controlling the movement of each of said members axially and independently of the movement of the remainder of said members comprising a segmental frame having corners thereon and adapted to be passed about a cable and then rigidly closed, and a bushing adapted to have liquid forced thereinto at each of said frame corners for engaging the outer part of one of said members.

9. In a squeezer for suspension bridge cables, a hexagonal frame adapted to be opened for passage about a cable and moved from place to place on said cable, a series of similar built up frame segments each of less length than that of one side of said frame, a bushing at each corner of said frame between the ends of said segments, a member adapted to receive said bushing, flanges on said member arranged to enter into adjacent ends of adjacent segments, bolts detachably securing said flanges to said segments, a series of six compressor members mounted for bodily movement radially of said frame, and a cylindrical ram on each of said compressor members movable in said bushing and adapted to have hydraulic pressure put thereon for moving one of said compressor members independently of the other compressor members for putting pressure on the cable.

HOLTON D. ROBINSON.
